UNITED STATES PATENT OFFICE

DAVID C. ROCKOLA, OF CHICAGO, ILLINOIS

DESIGN FOR A WEIGHING MACHINE CASING

Application filed September 12, 1931. Serial No. 41,073. Term of patent 14 years.

To all whom it may concern:

Be it known that I, DAVID C. ROCKOLA, a citizen of the Dominion of Canada, residing at Chicago, in the county of Cook and State of Illinois, have invented a new, original, and ornamental Design for Weighing Machine Casings, of which the following is a specification, reference being had to the accompanying drawing, forming part hereof.

The figure is a perspective view of the weighing machine casing, showing my new design.

I claim:

The ornamental design for a weighing machine casing, as shown.

DAVID C. ROCKOLA.
